PHILIP STAATS CARTER, OF PORT JEFFERSON, NEW YORK, ASSIGNOR TO RADIO CORPORATION OF AMERICA, A CORPORATION OF DELAWARE

FEEDING SYSTEM

Application filed May 14, 1930. Serial No. 452,195.

This invention relates to a feeding system and has as one of its objects the provision of a new and useful method and means for supplying energy to an antenna system having a plurality of radiating elements one of which may be considered an antenna, and the other of which may be considered an energized reflector therefor.

In order to obtain efficient unidirectional radiation, energized radiating elements are used spaced apart an odd number of quarter wave lengths. For maximum efficiency, it is necessary that the power radiated is equal in each of the elements and at a predetermined correct phase relationship. In order to energize the antenna and reflector forming part of the system outlined, supply lines connected to each radiating element, tied together at some point and connected to a transmission line leading to a source of high frequency energy, are supplied with energy from the source. In order to obtain correct power distribution heretofore, one of the radiating elements was matched to its supply line and subsequently the other radiating element was matched to the other supply line. After both were matched it was found, upon testing the first supply system, that it was unmatched, because of various interactions caused during the matching of the second system and the reaction between the reflector and antenna. As a consequence of this, tuning of the antenna and reflector and matching thereof became a juggling process, never exact and requiring long periods of time to obtain even approximately correct adjustment.

An object of the present invention is to overcome the foregoing difficulties and to provide a method of coupling radiating elements to their supply lines in much simpler and quicker fashion than done heretofore and which will give correct power distribution and phase relationship for unidirectional electro-magnetic wave propagation. Briefly, this object is accomplished by untying or leaving free the supply lines at their junction point, and alternately matching and tuning the radiating elements of the respective supply lines. Then, when this is finally accomplished, the supply lines may be connected to-

gether at any point and there will be correct power distribution and phase relationship of the energy in the radiating elements; namely, the antenna and reflector, to give the desired propagation.

The invention as outlined briefly in the foregoing statements may be more fully understood by the remarks which are to follow directed particularly towards the accompanying drawings, in which

Figure 1 illustrates a transmission line terminated by a non-reactive impedance,

Figure 2 illustrates a line similar to that given in Figure 1 but an odd number of quarter wave lengths shorter than the line of Figure 1,

Figures 3 and 4 indicate standing waves of current and potential in the lines shown in Figures 1 and 2 under certain conditions, and

Figure 5 discloses a radiating system incorporating the features of the present invention.

If the two lines *a*, *r*, shown in Figures 1 and 2, have a surge impedance equal to Z_0 and differ in length by any odd number of quarter wave lengths, and line *a* is loaded with a resistance equal to $k \times Z_0$ and line *r* loaded with a resistance

$$\frac{1}{k} \times Z_0,$$

then, standing waves will be set up on the lines *a*, *r*. Assuming *k* to be less than unity, the load *A* on line *a* approaches a short circuit as a result of which there is a potential minimum and a current maximum at point *A* as shown in Figure 3.

As the load *R* on line *r* approaches infinite impedance, or an open circuit, there will be, as shown in Figure 4, a maximum potential and a minimum current value at point *R*. From the curves of Figures 3 and 4 it should be apparent, therefore, that the impedance along adjacent points of lines *a*, *r* is the same and that they may be coupled, connected or tied together in any suitable fashion.

The foregoing conditions exist in the case of the antenna system shown in Figure 5, where loads *A* and *R* are independently non-reactive, but mutually reactive. Supply

lines a' , r' feed through impedance matching devices 2, 4, antenna A and reflector R respectively. Because of the spacing of the antenna A and reflector R line a' is an odd number of quarter wave lengths longer than line r' . This is indicated by the factor n on the drawings which indicates any odd number. The supply lines a' , r' are fed from a transmission line T from a source S of high frequency current through impedance matching device 6 which connects transmission T to the tying point 8 of lines a' and r' .

Now, in the system described in Figure 5, by virtue of the mutual action between the antenna and reflector when energized, the impedance of the antenna is caused to decrease and, the impedance of the reflector is caused to increase. Since action and reaction are always equal and opposite, if the antenna impedance is decreased by a certain ratio k , reaction on the reflector will cause an increase in its impedance according to the ratio

$$\frac{l}{k}$$

Consequently, as the conditions outlined above in connection with Figures 1 to 4 for the tying together of lines a , r , are satisfied, lines a' and r' , of Figure 5, may be tied together at any point 8. Tying, according to this invention is done after antenna A has been tuned, in which condition it presents a resistive load, and matched to line a' with reflector r short circuited, detuned or otherwise unenergized and disconnected. Similarly and subsequently antenna A is disconnected and deenergized, and reflector R is tuned and matched to its line r' . Still later, at tying point 8, the antenna system may be matched by means of impedance matching device 6 to transmission line T to which it is connected.

Tying together of lines a' and r' at any point 8 after the tuning and matching procedure outlined has been carried out may be done by virtue of the fact that it can be demonstrated that if two similar transmission lines differing in length by an odd number of quarter wave lengths are loaded with resistances, one having the ratio K to the surge impedance and the other having the inverse ratio

$$\frac{l}{k}$$

to the surge impedance, the impedance offered at the input ends are identical regardless of the actual total length.

This is, in order to properly couple the system shown in Figure 5, the reflector R, after being thrown out of tune is left disconnected from its supply line r' and unenergized while the antenna impedance is matched by impedance matching device 2 to the surge im-

pedance of line a' and the antenna tuned. The antenna is then disconnected from its line, short circuited or detuned, and the reflector is tuned, connected to its line r' and matched thereto through its impedance matching device 4. Now, if the supply lines a' and r' after removal of short circuits and disconnections are tied together at any point such as 8, the high frequency power from source S will divide equally and in correct phase between the antenna and reflector despite the fact that by virtue of their mutual action their impedances are no longer equal; for, although the current in the reflector causes a decrease in the antenna impedance, the current in the antenna causes an increase in the reflector impedance and reflection takes place on both lines, due to the fact that the antenna and reflector are separated by an odd number of quarter wave lengths, the impedances at the point where lines a' and r' are connected together are equal and consequently power from source S divides equally between the two lines.

Proper current division and correct phase relation can theoretically be obtained by first connecting lines together at point 8 but it is a long and difficult process, when A is matched to its line, adjustment of matching circuit for R throws out the matching of A. Then, when A is readjusted R goes out etc. This, all due to action and reaction of radiation from A on R and from R on A. After several see-saw adjustments correct result can be approximately obtained.

I claim:

1. In a system comprising a pair of elements, independently non-reactive when supplied with energy of a certain frequency but mutually reactive at that frequency; a source of energy; and, separate lines from the source to each of the elements; the method of coupling the system together which includes alternately deenergizing one element while matching the other to its supply line and then tying the lines together.

2. In a radiating system comprising a pair of radiating elements, a source of energy, and separate lines from the source to each of the radiating elements, the method of coupling the apparatus together which includes deenergizing one radiating element while matching at a predetermined frequency the other element to its supply line, deenergizing the matched element while tuning and matching at the same aforementioned frequency the formerly deenergized element to its supply line and subsequently coupling the two supply lines together.

3. In a radiating system comprising an antenna, a reflector, a source of energy, and lines from the source to the antenna and reflector for energizing the same, the method of coupling the antenna and reflector to the source which includes deenergizing the re-

5 reflector, matching at a predetermined frequency the impedance of the antenna to its supply line, deenergizing the antenna, matching at the same aforementioned frequency the impedance of the reflector to its supply line with the antenna deenergized, and coupling the supply lines together.

10 4. In a radiating system comprising a pair of tuned radiating elements, a source of energy for exciting the elements and supply lines for supplying energy from the source to the elements, the method of connecting the source, lines, and the elements together which includes alternately deenergizing the elements while matching at the same frequency the remaining tuned element to its respective supply line, tying the supply lines together after matching at the same frequency each element to its supply line and connecting the 15 source to the supply lines at the tying point.
